UNITED STATES PATENT OFFICE.

HEINRICH WILHELM HELLMANN AND OSKAR ARENDT, OF BERLIN, GERMANY, ASSIGNORS TO GESELLSCHAFT FÜR HÄNGENDES GASGLÜHLICHT M. B. H., OF BERLIN, GERMANY, A CORPORATION.

INVERTED GAS-LIGHT INCANDESCENT LAMP.

No. 801,456.

Specification of Letters Patent.

Patented Oct. 10, 1905.

Application filed October 27, 1903. Serial No. 178,803.

To all whom it may concern:

Be it known that we, HEINRICH WILHELM HELLMANN, engineer, residing at 7 Zinendorfstrasse, and OSKAR ARENDT, civil engineer, residing at 216 Friedrichstrasse, in Berlin, in the Kingdom of Prussia, German Empire, have invented certain new and useful Improvements in Inverted Gas-Light Incandescent Lamps; and we do hereby declare the nature of our invention and in what manner the same is to be performed to be particularly described and ascertained in and by the following statement.

Our present invention is relative to a gas incandescent-light lamp burning downward, being characterized by a plate with outlets for the rising hot combustion-gases being arranged immediately above the glass bulb and the hot gases being sucked out of the bulb with a draft analogous to that of a chimney.

By the aid of the following description, as well as of the annexed diagram, our invention has been fully exposed.

The drawing shows a longitudinal section of the invention.

In the inverted gas-lamp shown in the figure in longitudinal section a screening-off or deflecting plate 14 is arranged upon the burner-head 7, which is preferably made of fire proof heat-non-conducting material. The plate 14 may, if desired, be formed in one piece with the burner-head 7, but could also be arranged on another place of the mixing-tube. The transparent protecting-bulb 32, which surrounds the incandescent body 11, is suspended immediately below the screening-off and deflecting plate 14 and from a three or more armed supporting-yoke 33, fastened to the mixing-tube 1. Upon the outer rim of the plate 14 we provide outwardly-opening inclined perforations and tubes 15, the number of which may be different, according to their inner diameter, and which may be arranged in any suitable manner. The hot gases of combustion ascending from the mouth of the burner and from the incandescent body are deflected away laterally through the said tubes. The deflecting-surface of the plate 14 is decreased by the said inclined tubes, so as to prevent any harmful stagnation of the ascending hot gases of combustion, and we thereby also avoid heating the plate 14 to an unduly high

temperature. The chimney-draft created by the tube extensions produces the flow to 55 the mouth of the burner of a powerful supply of air through the lower openings of the lamp-shade, the draft causing the ascension of the hot gases of combustion in the interior of the shade 32, and by this means the illuminating power of the incandescent body 11 is increased. By means of caps, stoppers, or covers 34 one or the other of the exit-openings may be covered or may be partially closed. 65

Having now particularly described and ascertained the nature of our said invention and in what manner the same is to be performed, we declare that what we claim is—

1. In an incandescent gas-lamp the combination of a mixing and burner tube, a burner-head at the lower end of the burner-tube, an incandescent body round the burner-head, a transparent protective bulb surrounding the incandescent body, means for 75 fastening the said bulb on the mixing-tube a deflecting-plate immediately above the transparent protective bulb this plate having a larger diameter, than the outlet-opening of the said protective - bulb plate outwardly- 80 opening tube extensions above the perforations of the deflecting-plate substantially as and for the purpose described.

2. In an incandescent gas-lamp the combination of a mixing and burner tube, a 85 burner-head at the lower end of the burner-tube, an incandescent body round the burner-head, a transparent protective bulb surrounding the incandescent body, means for fastening the said bulb on the mixing-tube a 90 deflecting-plate immediately above the transparent protective bulb this plate having a larger diameter, than the outlet-opening of the said protective - bulb plate outwardly- 95 opening tube extensions above the perforations of the deflecting-plate covers for the tube extensions substantially as and for the purpose described.

In witness whereof we have hereunto set our hands in the presence of two witnesses. 100

HEINRICH WILHELM HELLMANN.
OSKAR ARENDT.
